UNITED STATES PATENT OFFICE.

CHARLES DOWNEY LYON, OF ST. LOUIS, MISSOURI, ASSIGNOR OF ONE-HALF TO
FLORENCE E. WOLF, OF ST. LOUIS, MISSOURI.

SOUND-INTENSIFIER.

1,114,493.

Specification of Letters Patent. Patented Oct. 20, 1914.

Application filed June 13, 1912. Serial No. 703,407.

To all whom it may concern:

Be it known that I, CHARLES DOWNEY LYON, a citizen of the United States, residing at the city of St. Louis, State of Missouri, have invented certain new and useful Improvements in Sound-Intensifiers, of which the following is a specification.

This invention relates to improvements in telephone attachments, and consists of a more efficient sound intensifier for the transmitter.

The present invention provides an improved sound intensifier that is simple and inexpensive to manufacture and easy to attach to the ordinary mouth-piece of a telephone.

Usually when an ordinary sound intensifier is used in connection with the transmitter of a telephone a special mouth-piece must be used and the sound intensifier securely fastened therein, but, when the improved sound intensifier of the present invention is used, the necessity of providing a special mouth-piece is obviated, as the intensifier can be attached to the ordinary mouth-pieces.

Further, the present invention resides in the novel means for attaching the sound intensifier to the mouth-piece of a telephone transmitter.

With these objects in view, the present invention consists of the novel features of construction and arrangement of parts that will be hereinafter more fully described and pointed out in the claims.

In the accompanying drawings forming part of this specification, in which like numbers of reference denote like parts wherever they occur, Figure 1 is a perspective view of an improved sound intensifier embodying the present invention; Fig. 2 is a sectional view of an ordinary mouth-piece with this improved sound intensifier attached thereto; Fig. 3 is a rear elevation of the mouth-piece with this improved sound intensifier attached thereto; Fig. 4 is a perspective view of the improved sound intensifier showing an alternate form of means of attachment therefor; Fig. 5 is a sectional view of an ordinary mouth-piece with same attached thereto; Fig. 6 is a perspective view of the improved sound intensifier, showing an alternate form of means of at-

tachment therefor; and Fig. 7 is a sectional view of an ordinary mouth-piece with same attached thereto.

The improved sound intensifier of the present invention consists of a thin hollow shell 1, which may be formed of metal, such as aluminum or the like or any other suitable material. The shell 1 is preferably formed with somewhat of a semi-ellipsoidal configuration, the small or front end of which is closed and is preferably pointed for the purpose hereinafter described. The large or rear end of the shell 1 is open and has a lug 2 or a plurality of such lugs formed on the rim of same. A finger or projection 3 may be formed upon one or any number of the lugs 2, so as to afford a means for attaching the shell 1 to the mouth-piece 4 of a telephone transmitter or other sound transmitting device in the manner herein-after described, such, for instance, as a phonograph or a dictograph or any other sound transmitting instrument.

For the purpose of illustration, one way of arranging the lugs 2 and fingers 3 is depicted in the drawings, but it should be understood that this arrangement may be varied, if desired, i. e., while the shell 1 is provided with four lugs, yet the number may be increased or decreased as may be desired. In the arrangement illustrated in the drawings, two of the lugs 2 that are located diametrically opposite each other are provided with fingers 3, but, if desired, a finger may be formed upon only one of said lugs or upon any number or all of said lugs.

Ordinarily, the mouth-piece 4 of a telephone transmitter is detachably secured in place, and has a wall or diaphragm 5 containing a plurality of perforations 6, through which the sound waves pass from the mouth of the speaker to the transmitter diaphragm (not shown), some of said perforations being located near the inner side walls of said mouth-piece and others near the center of said wall 5. In order to attach the sound intensifier to the mouth-piece 4, it is only necessary to detach the mouth-piece from the telephone, and hold the shell 1 in such position that the pointed end thereof will be toward the speaker and each finger 3 borne by the rear end of same in registration with a perforation 6 in the wall 5.

of said mouth-piece and insert the sound intensifier into the open front of said mouth-piece far enough to cause each finger 3 to enter the particular perforation 6 in registration therewith and, also, to cause each lug 2 to rest against the front face of said wall. The fingers 3 are of such length that, when the shell 1 is inserted into the mouth-piece 4 far enough to cause the lugs 2 to rest against the front face of the wall 5 as just described, each finger 3 will extend entirely through a perforation 6 and will project beyond the rear face of wall 5, after which each finger may be bent against the rear face of said wall in the manner depicted in Figs. 2 and 3, or any other suitable manner, with the result of holding the shell 1 firmly in place in the mouth-piece 4, which may then be attached to the telephone in the usual manner. The lugs 2 are preferably arranged so that same will be the particular parts of the shell 1 that touch the front face of wall 5 and, also, so that a space 7 will be left between each two adjacent lugs, in order to allow the sound waves to pass through the perforations 6 near the inner side walls of the mouth-piece 4. The shell 1 is located in the middle of the mouth-piece 4 and is of such size that an annular space is left between same and the walls of said mouth-piece when said shell is attached to said mouth-piece as hereinabove described. If desired, however, the fingers 3 may be formed of resilient metal and bent so that the shell 1 can be attached to the mouth-piece 4 without the necessity of removing the latter from the telephone. When the shell 1 is provided with spring fingers 3, the latter may project outwardly, as depicted in Figs. 4 and 5, in which case it is only necessary to press same inwardly in order to insert same into the perforations 6 in the wall 5 of mouth-piece 4, or said fingers may project inwardly, as depicted in Figs. 6 and 7, so that, in order to attach the shell 1 to said mouth-piece, it is only necessary to press said fingers outwardly until same enter the perforations 6 in wall 5. In either case, after the fingers are inserted into perforations 6 in wall 5 of mouth-piece 4, the resiliency of said fingers holds the shell 1 in place in said mouth-piece in an obvious manner. In case it is desired to attach the sound intensifier to a mouth-piece in the absence of perforations or the like, the fingers 3 may be formed with such length that same will engage the sides of the mouth-piece, and thereby hold the device in place.

When a person talks into the mouth-piece 4 of a telephone transmitter that is equipped with one of these sound intensifiers, the sound waves will strike against the pointed end of the shell 1, which, in turn, will cause same to spread and pass through the annu-

lar space around said shell and then through the spaces 7 into the perforations 6 adjacent the inner walls of said mouth-piece. The sound waves then pass through said perforations and strike the transmitter diaphragm, from which same rebound and pass through the perforations 6 near the center of the wall 5 into the interior of shell 1. The sound waves that enter the shell 1 as just described are destroyed within same by reason of the concentrating effect of the tapered inside of the shell, and are thereby prevented from interfering with or coming in contact with the sound waves that follow same into the mouth-piece 4. By means of this device, the sound waves that enter the mouth-piece 4 have a free passage to the transmitter diaphragm without being hindered or weakened by the sound waves that strike the transmitter diaphragm and rebound therefrom, and a conversation held over telephones that are equipped with same is rendered more audible than when same are not used. Furthermore, these devices render even a whispered conversation so distinct as to give a privacy to the speaker which could in no simpler or more effective way be obtained.

By reason of using a shell 1 having a pointed end, said shell is more effective in causing the sound waves to spread and pass around same toward the transmitter diaphragm than a shell having its end rounded or formed with any other shape. This is due to the fact that the pointed shell offers less resistance to the sound waves than a shell having any other shape, and consequently reduces the friction to the minimum. Furthermore, the pointing end of the shell 1 forms a tapered interior, which is more effective in concentrating the sound waves toward the pointed end in order to destroy same when caught in said shell.

I claim:

1. A sound intensifier comprising a hollow shell bearing spacing lugs on the edge thereof, said lugs being for engagement with the diaphragm of a sound transmitter mouth piece to space said edge from the diaphragm to provide passages that conduct sound waves to the diaphragm and having means for attaching said shell to said diaphragm.

2. In a telephone, the combination with the mouth-piece thereof having a perforated diaphragm of a sound intensifier comprising a hollow shell located within said mouth-piece and having a lug on the edge thereof resting against said diaphragm and a finger borne by said lug extending through a perforation in said diaphragm and being bent so as to secure said shell to said diaphragm.

3. In a telephone, the combination with the mouth-piece thereof having a perforated diaphragm of a sound intensifier comprising

a hollow shell having lugs on the edge thereof resting against one side of said diaphragm and fingers borne by some of said lugs extending through perforations in said diaphragm and being bent on the other side of said diaphragm to secure said shell to the latter.

4. In a telephone, the combination with the mouth-piece thereof having a perforated diaphragm of a sound intensifier comprising a hollow shell having lugs on the edge thereof resting against one side of said diaphragm and fingers borne by some of said lugs extending through perforations in said diaphragm and being bent on the other side of said diaphragm to secure said shell to the latter, there being a space between each two adjacent lugs to allow the sound waves to pass through the perforations in said diaphragm.

5. A sound intensifier composed of a hollow shell formed with spaced lugs on the edge thereof for engagement with the diaphragm of the mouth piece of a sound transmitter, and bendable fingers borne by some of said lugs for extension through perforations in said diaphragm and for engagement with the rear side thereof.

6. A sound intensifier composed of a hollow shell formed with integral spaced projections to engage the diaphragm of the mouth piece of a sound transmitter, and bendable fingers for extension through per-

forations in said diaphragm and for engagement with the rear side thereof. 35

7. A sound intensifier composed of a hollow shell, formed with integral lugs and integral fingers, the lugs being for engagement with the outer side of the diaphragm of the mouth piece of a sound transmitter 40 and the fingers for engagement through the perforations thereof.

8. A sound intensifier composed of a hollow shell having integral bendable means formed on its free edge for projection 45 through the perforations of the diaphragm of a sound transmitter mouthpiece and for engagement with the rear side of said diaphragm.

9. In a telephone, the combination, with 50 a mouthpiece having a perforated end wall, of a sound conserver comprising a shell-like member located within said mouthpiece and having an extending portion on the edge thereof to engage a perforation in said end wall so as to secure said member thereto, and a lug formed integral with said member and adapted to engage said end wall. 55

In testimony whereof, I have hereunto signed my name to this specification in the presence of two subscribing witnesses. 60
